UNITED STATES PATENT OFFICE.

THOMAS F. DEEGAN, OF PHILADELPHIA, PENNSYLVANIA.

RAILWAY EQUIPMENT.

Application filed February 28, 1924. Serial No. 695,688.

To all whom it may concern:

Be it known that I, THOMAS F. DEEGAN, a citizen of the United States, residing at Philadelphia, county of Philadelphia, and 5 State of Pennsylvania, have invented certain new and useful Railway Equipment, of which the following is a specification.

Generally stated, this invention relates to railway equipment and has more especial 10 relation to means for securing together as a unit a railway tie, a tie-plate and a rail.

As at present practiced it is customary to use a squared spike which is driven into a wooden tie for securing a rail in place. 15 In driving a squared spike into a wooden tie the fibre of the wood is broken down to such an extent that weather conditions cause rotting of the broken down fibres which eventually results in the spike becoming so loosened as to be ineffective. In 20 other words, as rolling stock passes over the rail sections the spikes are ineffective to offer resistance. This results in lifting of the spikes above the flange of the rail and 25 is only rectified by careful watching of the track walkers. When the spikes are lifted from the flanges of the rail the tie-plates are also lifted from the tie. As a result, the tie-plates continuously move independently 30 of the rail and tie with the effect that within a short time the mechanical life of the tie is destroyed. The tie-plate movement caused by the loosened spikes causes lateral movement of the ties with the 35 effect that they are driven sidewise in the ballast and road bed which also tends to destroy the efficiency of the road bed. I have discovered that in order to have a road bed in condition to insure safety and to 40 reduce the cost of maintenance it is absolutely necessary that a tie, tie-plate and rail must be secured together as a unit so that when rolling stock is passing over the rail any depression of the rail will result in the 45 entire depression of the entire unit and that after rolling stock is passed over the rail- ing parts will rise as a unit.

In order to overcome the first above de- 50 scribed disadvantageous features and to secure the beneficial results thereof set forth is the leading object of the present inven- tion—

Other and further objects not at this 55 time more particularly pointed out will be hereinafter referred to.

The invention consists of the novel con-

struction hereinafter described and finally claimed.

The nature, characteristic features and scope of the invention will be more fully 60 understood from the following description taken in connection with the accompanying drawings forming part hereof, and in which:

Fig. 1, is a fragmentary view in cross-section illustrating a railway tie, tie-plate and rail together as a unit in accordance with the present invention.

Fig. 2, is a similar view illustrating the manner of introducing the improved spike 70 of the present invention.

Fig. 3, is a sectional plan view of the upper portion of my improved spike, and

Fig. 4, is a similar view of the lower portion of my improved spike, and Figs. 5 75 and 6 illustrate in plan and elevation, respectively, the complete arrangement of parts shown in the preceding figures.

For the purpose of illustrating my invention I have shown in the accompanying 80 drawings one form thereof which is at present preferred by me, since the same has been found in practice to give satisfactory and reliable results, although it is to be understood that the various instrumentalities of 85 which my invention consists can be variously arranged and organized and that my invention is not limited to the precise arrangement and organization of the instrumentalities as herein shown and described. 90

According to the present invention, instead of driving a railway spike directly into a wooden tie I drill in the tie 1 at time of manufacture one or more openings 2, see Fig. 2. These openings 2 are of 95 smaller diameter than the spike to be driven thereinto. The spike of the invention is best seen in Figs. 1, 3 and 4. The upper portion of the spike is of rectangular configuration as designated by numeral 3, and the lower portion of the spike is of oval shape as designated by the numeral 4. The head 5 of the spike is of conventional form. The lower end of the spike may have a chisel point or a round point. The oval 105 shaped portion 4 of the spike is serrated as at 6. These serrations are made while the spike is hot in the process of manufacture. It is to be observed that the squared portion of the spike is adapted to abut against the 110 edge 7 of the rail 8 and that the tie-plate is apertured as at 9 for the passage there-

through of a spike. To assemble the parts above described the ties are properly drilled and positioned each with a tie-plate 10 thereon, the apertures of the tie-plate being 5 in register with the drill openings 2 in the ties. With the rails 8 properly positioned a spike is then inserted through the tie-plate and driven into the tie. Since the diameter of the spike is in excess of the diameter of the opening 2 the serrated portions 10 of the spike spread the walls of the opening 2 and form a tight fit with the tie. The serrated portions become imbedded in the tie and thereby firmly secure the tie, tie-plate and rail together as a unit. The 15 squared portion 3 of the spike prevents rotation of the spike about its vertical axis because of this abutting position with the edge 7 of a rail. By the above arrangement and construction rolling stock passing 20 over a rail moves all the parts downwardly together as a unit and after the rolling stock has passed thereover the above described parts rise as a unit. Thus safety in operation, comfort in travel, and general efficiency 25 is provided. Should, for any reason, a spike become loosened it may be withdrawn from a drill hole in the tie and the tie plugged with a hard, wooden plug and another spike 30 driven into the tie. It will be apparent that instead of the oval shaped spike I may use a round spike, and that instead of the serrated surface a spike having a plain surface may be employed.

35 The tie plate 10 before described is of special construction, extending almost the entire length of a tie instead of in two sections as at present employed. By the one-piece, elongated construction both rails are 40 locked with respect to a tie-plate and a tie. Spikes 11 are employed to secure the tie-plate to a tie. The outer end of each tie-plate is provided with a flange 12 against 45 which the outer flange of a rail abuts. Thus the tendency of rails to spread is eliminated

as both rails are fixed to a tie-plate and tie to complete a unit. Such construction is particularly useful upon a curved track where severe thrust and strain are present.

In conclusion it is safe to say that on a 50 straight track, with the described tie-plate fastened to the tie with an oval spike driven into the bored, round hole in the tie, and fastened to the rail with sound ties, there can be maintained a good safe road-bed. 55 With the tie-plate, herein described, upon curves as absolutely safe road-bed can be had or made for any heavy equipment and increased speed with a great saving in maintenance of road-bed expenses. 60

It will now be apparent that I have devised a novel and useful construction which embodies the features of advantage enumerated as desirable in the statement of the invention and the above description and while 65 I have in the present instance shown and described the preferred embodiment thereof which has been found in practice to give satisfactory and reliable results, it is to be understood that the same is susceptible of 70 modification in various particulars without departing from the spirit or scope of the invention or sacrificing any of its advantages.

Having thus described my invention, what 75 I claim as new and desire to secure by Letters Patent, is:

In railway equipment the combination of 80 a railroad tie having a hole drilled vertically therein, a tie-plate having a hole in register with the tie opening, a rail upon 85 said tie-plate and a spike having a squared upper portion and an oval and serrated lower portion of a diameter larger than that of the tie opening penetrating said openings 85 for locking said parts together as a unit.

In testimony whereof, I have hereunto signed my name.

THOMAS F. DEEGAN.
